BLIND-STITCHING PRESSER-FOOT FOR
ZIG-ZAG SEWING MACHINES

Paul Boguhn, Berlin, and Richard Bochmann, Wittenberge, Potsdam, Germany, assignors to The Singer Manufacturing Company, Elizabeth, N. J., a corporation of New Jersey

Application March 23, 1937, Serial No. 132,458
In Germany September 19, 1936

4 Claims. (Cl. 112—151)

This invention relates to a blind-stitching presser foot for zigzag sewing machines fitted with a vertically yieldable work-guiding member, and has for an object to provide an improved construction in which the work-guiding member can rise and fall readily with variations in the thickness of the work.

According to the invention the work-guiding member is pivotally supported by the foot at the forward end of said member, i. e., at the end nearer to the operator.

In a practical construction the pivot for the work-guiding member is journaled in bosses of a bracket fitted to one toe portion of the bifurcated presser foot so as to be adjustable transversely of the direction of feed. The work-guiding member is thus laterally adjustable besides having freedom to rise and fall in the gap between the toe portions of the foot.

20 A torsion spring coaxial with the pivot of the work-guiding member urges the work-guiding member in downward direction.

In the accompanying drawing, Fig. 1 is a front elevation of a blind-stitching presser foot embodying the invention, Fig. 2 a side elevation, Fig. 3 a top plan view, and Fig. 4 a vertical section on the line *a*—*b* of Fig. 3 showing the presser foot operatively engaging a blind seam in course of formation. Figs. 5 and 6 are detail perspective views illustrative of the formation of the blind seam.

Referring to the drawing, the improved blind-stitching presser foot, which is adapted to be secured to the presser-bar in the usual way, consists of the shank 1 and the sole 2, the latter being bifurcated to constitute an upturned toe member 3 of the usual form and a complementary laterally enlarged member or plate 15. Formed in the upper face of the plate 15 is a slideway 14 in which is fitted to be adjustable transversely of the direction of feed a bracket 8 formed with an elongated slot 16 through which passes the stem of a headed screw 17 threaded into an orifice in the plate 15 and serving to secure the bracket 8 in its position of adjustment.

45 At its forward end the bracket 8 is formed with two co-axial spaced bosses 6 and 7 in which is journaled a pivot-pin 5 carrying on its left-hand end the work-guiding member 4 which is movable vertically, about the axis of the pivot-pin 5, in the gap between the toe portion 3 and the plate 15. The pivot-pin 5 is secured against axial shift relatively to the bosses 6 and 7 by a cotter 9. That portion of the pivot-pin 5 extending between the bosses 6 and 7 is embraced by a torsion spring 11 one end of which is anchored to the bracket 8 and the other out-turned end 13 of which enters an orifice 10 in the work-guiding member 4, urging the member 4 downwardly below the plane of the sole 2. Excessive

displacement of the member 4 under the action of the spring 11 is limited by the end 13 of the spring engaging the upper face of the bracket 8.

As will be seen from Fig. 2, the member 4 is deeper at its rearward end, than at its forward end.

By loosening the screw 17 and sliding the bracket 8 in the slideway 14 of the plate 15, the member 4 can be adjusted laterally in relation to the needle 19 as required for blind stitching materials 10 of different thicknesses and according to the kind of work to be performed.

The sole 2 is preferably formed on its under face with a groove 18 extending in the direction of feed in a region behind the needle 19, in the left-hand position of the needle, and to the left thereof, so that the fabric may be properly guided during the blind-stitching operation, as shown in Fig. 4.

What is claimed is:

20 1. The combination with a sewing machine presser-foot having spaced toe portions one of which is formed in its upper face with a slideway, of a bracket adjustable in said slideway transversely of said toe portions, and a vertically yieldable work-guiding member pivoted at its forward end to said bracket with freedom to rise and fall in the space between said toe portions.

25 2. The combination with a sewing machine presser-foot having spaced toe portions one of which is formed in its upper face with a slideway, of a bracket adjustable in said slideway transversely of said toe portions, means for securing said bracket in its position of adjustment, and a vertically yieldable work-guiding member pivoted at its forward end to said bracket with 30 freedom to rise and fall in the space between said toe portions.

35 3. The combination with a sewing machine presser-foot having spaced toe portions one of which is formed in its upper face with a slideway, of a bracket adjustable in said slideway transversely of said toe portions, said bracket formed with bosses, a work-guiding member unitary with a pivot journaled in said bosses and having freedom to rise and fall in the space between said toe portions, said work-guiding member extending rearwardly from said pivot, and spring means 40 urging said member in downward direction.

45 4. A sewing machine presser-foot having a shank, a sole-plate carried by said shank and formed with a needle-opening and spaced toe-ports in advance of the needle-opening, a bracket laterally adjustably mounted on one of said toe-ports, and a blind-stitching edge-guide pivoted at its forward end to said bracket 50 with freedom to rise and fall in the space between said toe-ports.
